UNITED STATES PATENT OFFICE.

PAUL DUDEN AND GUSTAV PETERS, OF HÖCHST-ON-THE-MAIN, GERMANY, ASSIGNEES
TO FARBWERKE VORM. MEISTER LUCIUS & BRÜNING, OF HÖCHST-ON-THE-MAIN,
GERMANY, A CORPORATION OF GERMANY.

PROCESS OF PREPARING ACETALDEHYDE FROM ACETYLENE.

RE. 14,063.

Specification of Reissued Letters Patent. Reissued Feb. 15, 1916.

No Drawing. Original No. 1,151,928, dated August 31, 1915, Serial No. 2,076. Application for reissue filed January 4, 1916. Serial No. 70,284.

To all whom it may concern:

Be it known that we, PAUL DUDEN, Ph. D., professor of chemistry, and GUSTAV PETERS, Ph. D., chemist, citizens of the Empire of Germany, residing at Höchst-on-the Main, Germany, have invented certain new and useful Improvements in the Process of Preparing Acetaldehyde from Acetylene, of which the following is a specification.

10 In the manufacture of acetaldehyde from acetylene in presence of solutions containing mercury the latter gradually separates from the solutions in a metallic form owing to secondary reactions. In consequence there-
15 of the absorption of the acetylene and the formation of the aldehyde are retarded accordingly as the separation of the metal occurs and finally cease completely if no fresh quantity of mercury salt or mercury
20 oxide be added. The separated metallic mercury has hitherto been isolated and re- transformed into mercury salts or into mercury oxids by means of concentrated acids or by anodic oxidation, and again intro-
25 duced into the circuit of the process. This regeneration of the active mercury com- pounds, which must be effected separately,
30 was very laborious from a technical point of view and entailed considerable losses of mer-
cury. Now we have found that the said draw-
backs can be entirely avoided by adding to the liquid of the reaction from the beginning of the process or in the course of it such an oxidizing agent as, on the one
35 hand, impedes the separation of the mer-
cury and, on the other hand, is not able under the working conditions employed, to oxidize to an appreciable extent either the acetylene, or the intermediately produced
40 mercury-compounds of acetylene, or the aldehyde.

In our new process ferric compounds may, in the first place, be considered as technically suitable oxidizing agents. By the
45 addition of them, the mercury separating in an extremely finely-subdivided form is re-

transformed in the nascent state into its active salt. The process can be continuously carried on by drawing off from time to time the resulting saturated solution of ferrous salt which is free from mercury and returning the same into the circuit of the process after having re-oxidized it to the ferric state, for example by atmospheric oxidation.

The following example illustrates our in-
vention: 3 liters of sulfuric acid of about
6% strength and 90 grams of mercury sul-
fate and a small quantity of ferric sulfate
are mixed in a vessel provided with a
stirrer, cooling device and a receiver, and
through this mixture a strong acetylene cur-
rent is passed which carries along with it
the acetaldehyde produced. At the same
time a solution or a suspension of ferric
sulfate is run in, so that there is always an
excess of the oxidizing agent in the absorp-
tion-vessel. The absorption remains almost
constant for many hours and does not
diminish until the ferric sulfate contained
in the solution is converted entirely into
ferrous sulfate. The yield of aldehyde is al-
most quantitative.

Having now described our invention,
what we claim is:—

1. The process of preparing acetaldehyde from acetylene, which consists in combin-
ing acetylene with the elements of water in
presence of sulfuric acid, a mercury com-
pound, and an agent capable of impeding
the separation of mercury.

2. The process of preparing acetaldehyde from acetylene, which consists in combin-
ing acetylene with the elements of water in
presence of a mercury compound and a
ferric salt.

3. The process of preparing acetaldehyde from acetylene, which consists in combin-
ing acetylene with the elements of water in
presence of a mercury compound and ferric
sulfate.

PAUL DUDEN.
GUSTAV PETERS.
